[57] **CLAIM**

A flying disc, as shown and described.

DESCRIPTION

FIG 1 is a side elevation view of a flying disc showing my new design;

FIG. 2 is a top plan view thereof;

FIG. 3 is a bottom plan view thereof;

FIG. 4 is a sectional view thereof taken along line 4—4 of FIG. 2;

FIG. 5 is a side elevation view of a second embodiment of the flying disc of FIG. 1;

FIG. 6 is a top plan view of FIG. 5;

FIG. 7 is a bottom plan view of FIG. 5; and,

FIG. 8 is a sectional view of FIG. 5 taken along line 8—8 of FIG. 6.
